UNITED STATES PATENT OFFICE.

ULYSSES M. ORR, OF HENDERSONVILLE, NORTH CAROLINA.

DOLLY OR SKID ROLLER.

No. 901,028.

Specification of Letters Patent.

Patented Oct. 13, 1908.

Application filed January 4, 1908. Serial No. 409,347.

To all whom it may concern:

Be it known that I, ULYSSES M. ORR, citizen of the United States, residing at Hendersonville, in the county of Henderson and State of North Carolina, have invented certain new and useful Improvements in Dolly or Skid Rollers, of which the following is a specification.

The present invention provides a roller for supporting heavy machinery and loads, such as houses, during the process of moving the same, said roller being supplied with mountings of novel construction and which admit of the roller being turned to any angular position, and at the same time prevent backward rotation of the roller should the draft cables or ropes break, thereby preventing the house or load becoming unmanageable, or running away on a down grade, in the event of the draft rope parting or becoming loose from any cause.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a dolly or skid roller and mountings therefor embodying the invention. Fig. 2 is a vertical central transverse section thereof. Fig. 3 is a vertical central longitudinal section of the device. Fig. 4 is a horizontal section on a plane corresponding with the upper side of the flat ring, portions of the latter being broken away to show the opposite arrangement of the upper and lower ratchet teeth. Corresponding and like parts are referred to in the following description and indicated in all the views of the drawings by the same reference characters.

The roller 1 may be of any material and size and is preferably of wood and supplied with metal ends 2, which are flanged so as to embrace end portions of the roller, each end piece being provided with ratchet teeth 3 and an outer boss 4 through which a shaft 5

passes. The end pieces 2 are castings and the flanges 6 thereof embrace reduced end portions of the roller 1 so as to come flush with the surface thereof. The end pieces 2 being of metal reinforce the wooden roller 1, and materially assist in prolonging the life or period of usefulness, besides providing substantial means for the ratchet teeth 3, which coöperate with pawls 7 to prevent backward rotation of the roller. The shaft 5 is heavy and of steel and passes through the roller 1 and the metal end pieces 2, and is supported at its ends in pillow blocks or bearings 8. Anti-friction devices are interposed between the terminal portions of the shaft 5 and the bearings to cause the roller to turn with a minimum amount of resistance.

The framework for the roller consists of two parts, an upper frame and a lower frame, the latter consisting of a timber 9, and the upper frame consists of longitudinal timbers 10 and cross timbers 11, the several timbers 10 and 11 being bolted or connected in any substantial manner at their points of crossing. A flat ring 12 is secured to the underside of the upper frame, and is provided with upper ratchet teeth 13 and lower ratchet teeth 14. The flat ring 12 is of metal and constitutes the turn table upon which the upper frame turns when moving the same to adjust the roller 1 to the required angular position. The ratchet teeth 13 face in an opposite direction to the ratchet teeth 14 and a set of pawls 15 is provided to coöperate with the ratchet teeth 13, and a second set 90 of pawls 16 is provided for coöperation with the lower ratchet teeth 14, said pawls in conjunction with the ratchet teeth fixing the position of the upper frame and the roller. When the pawls 15 and 16 are moved out of engagement with the ratchet teeth 13 and 14, the upper frame may be turned to any position to enable the load resting upon the roller to be directed in the desired course. Plates 17 are secured to the upper side of the lower frame or timber 9 and are arranged to come directly beneath the flat ring 12, so as to receive the wear and sustain the perpendicular pressure of the load. A circular plate 18 is secured to the top side of the lower frame or timber 9 and is arranged midway between the plates 17 and concentric with the ring 12. A companion plate 19 is secured to the lower

side of the upper frame and rests upon the plate 18, the two plates 18 and 19 sustaining the wear and pressure of the load centrally of the upper and lower frames. A king bolt 5 20 passes through the upper and lower frames and the plates 18 and 19 and constitute the axis about which the upper frame turns. Corresponding openings 21 are provided in the upper and lower frames and are adapted 10 to receive pins 22 when it is required to fix the position of the upper frame so as to prevent any turning thereof, as when the load is to be moved in a direct line for a considerable distance. The lower frame is provided 15 with spurs 23 to penetrate the sill or sleeper upon which the dolly may be placed so as to prevent slipping. It is to be understood that any means may be provided and interposed between the lower frame and the surface 20 upon which it may be placed, so as to prevent slipping. The several pawls are spring actuated so as to automatically engage with the respective ratchet teeth. A metal bar 24 is attached to the upper 25 frame at each side of the roller as close to the bearings thereof as possible. These bars 24 materially strengthen the frame and secure it when the load is to one side or the other. The bars may be placed underneath 30 or on top of the frame as desired to secure the best results.

Having thus described the invention, what is claimed as new is:

1. In a device of the character specified, the combination of a lower frame, an upper frame mounted to turn upon the lower frame about a vertical axis, and provided with a load sustaining roller, a metal ring secured to one of the frames and provided with two sets of ratchet teeth facing in opposite directions, and pawls fitted to the other frame and coöperating with said ratchet teeth to secure the upper frame in an adjusted position.

2. In combination, a lower frame, an upper frame mounted upon the lower frame to turn about a vertical axis and provided with a load sustaining roller, a flat metal ring secured to the underside of the upper frame and provided with two sets of ratchet teeth 50 facing in opposite directions, pawls applied to the lower frame and coöperating with said ratchet teeth, and wear plates secured to the upper side of the lower frame and coming beneath the said flat ring.

55 In testimony whereof I affix my signature in presence of two witnesses.

ULYSSES M. ORR. [L.S.]

Witnesses:

A. CANNON,
P. V. CUNNINGHAM.
